UNITED STATES PATENT OFFICE.

RICHARD W. HUBBARD, OF ASHTABULA, OHIO.

HINGE.

1,309,629.

Specification of Letters Patent. Patented July 15, 1919.

Application filed June 11, 1918. Serial No. 239,427.

To all whom it may concern:

Be it known that I, RICHARD W. HUBBARD, a citizen of the United States, residing at Ashtabula, in the county of Ashtabula and 5 State of Ohio, have invented new and useful Improvements in Hinges, of which the following is a specification.

My present invention pertains to hinges, and is designed more particularly as an improvement upon the hinges constituting the subjects of my Patents Numbers 759,890 of 10 May 17, 1904, and 1,228,441 of June 5, 1917, respectively.

It consists first in the improved fins on the 15 shanks of the hinge members; the said fins being peculiar and advantageous in that they are thin at their bases—*i. e.*, where they are sheared or stamped out of the shanks and are correspondingly thin throughout 20 their width to their free longitudinal edges, with the result that they are adapted to be readily driven endwise into the wooden element in which the shank is countersunk.

Secondly it consists in the novel and practically advantageous manner of stiffening and strengthening the cover plates of the hinge and in the utilization of the stiffening and strengthening means to effect connection of the cover plates to their respective hinge 30 members.

The present invention further consists in the duplex and consequently strong hinge for use in situations where great strength on the part of hinges is necessary; the said hinge being made up of upper and lower 35 endwise opposed members, a single pintle common to the upper and lower members, and cover plates also common to the upper and lower members, each cover plate being 40 connected with an upper hinge member and a lower hinge member and being flatwise opposed to and connected with said members.

With the foregoing in mind the invention 45 will be fully understood from the following description and claim when the same are read in connection with the drawings, accompanying and forming part of this specification, in which:

Figure 1 is an elevation of a duplex hinge 50 embodying my present invention; the said hinge being shown as applied and with one of the cover plates removed.

Fig. 2 is a transverse section, taken in the

plane indicated by the line 2—2 of Fig. 1 and showing both cover plates in proper 55 relative positions.

Fig. 3 is a perspective of one of the cover plates *per se*.

Fig. 4 is a view illustrative of the sheared or stamped out fins and their relation to the 60 shanks.

Similar numerals of reference designate corresponding parts in all the views of the drawings.

Fig. 1 of the drawings shows a door casting 65 1 and a door 2, connected through the medium of my novel hinge.

The hinge illustrated as embodying my present invention is made up of a pintle 3, having a head 4, and upper members 5 and 70 6 and lower members 7 and 8 together with cover plates 9 of thin sheet metal suitable to the purpose. The members 5, 6, 7 and 8 are preferably of sheet metal, and generally 75 similar to the members disclosed in my Patent No. 1,228,441 *supra*. Each member has a knuckle or knuckles to receive the connecting pintle, and each has a shank 10, designed to be countersunk in a wooden element and connected thereto through the medium of a 80 screw 11 or the like. Each shank is equipped on its convex side, Figs. 2 and 4, with longitudinal fins 12 corresponding to the fins disclosed in my Patent 759890 *supra*. The said fins 12, however, differ from the fins 85 of the patent and are a material improvement over the same in that they are thin at the base—*i. e.*, where they are sheared or stamped from and form an integral part of the shank and are similarly thin throughout 90 their width to their free longitudinal edges. By virtue of such equal thinness throughout their areas the fins 12 are adapted to be expeditiously and easily driven endwise into the wooden element in which the shank is 95 to be countersunk, and this without liability of splitting the wood which obviously is a practical advantage. The said peculiar fins are also advantageous over those of the patent inasmuch as they are adapted to be embedded in wood without splitting thereof and hence are better calculated to hold the shank in and to the wood.

Each of the hinge members 5, 6, 7 and 8 is also peculiar in that it is provided at 13 105 in its body portion with notches, designed

and adapted to seat the complementary flange 14 of a cover plate 9.

A cover plate 9 is provided for coöperation with the members 6 and 8, and a similar cover plate for coöperation with the members 5 and 7, and from this it follows that the cover plates are adapted to serve not only to enhance the finished appearance of the hinge, but also to connect the upper members with the lower members so that each upper member and corresponding lower member will be tied together and caused to move as a unit; the plates 9 being connected by brads 15 to the wooden elements. It will also be observed that the flanges 14 of the cover plates by resting in the notches 13 of the hinge members will securely engage the cover plates and the hinge members, and at the same time will 20 lend increased stiffness and strength to the cover plates, tending to effectually prevent curling of the portions of the plates adjacent to the knuckles. On the other hand the said combination of notches and flanges 25 will assure the plates resting perfectly flat, as is desirable, and is further advantageous inasmuch as it obviates the necessity of having a plate for a male member of the hinge and another plate for a female member, 30 and renders it unnecessary for the carpenter to select a plate, either plate being adapted for use in engagement with either member. It will also be manifest that if the carpenter slips a piece of paper or the like between 35 the flanged end of a cover plate and the opposed knuckles it makes a very close joint, and this without scratching or marring of the knuckles.

It is to be understood in connection with 40 the foregoing that my fin improvement, and the combination of the flanged cover plate with the notched body portion of a hinge

member may be incorporated in a hinge made up of two pivotally connected members as distinguished from the duplex and 45 strong hinge herein disclosed, without involving departure from the scope of my invention as claimed.

I would have it understood that in the discretion of the parties manufacturing my 50 device, the flange 14 may be cut off a slight distance from their ends, in which case it will be unnecessary to slot the edges of the hinge at 13, and it will be readily appreciated that when such a cover plate is used, 55 the same will be in no way weakened and that the turned over portion will bear against the concave part of the edge of the hinge.

Having described my invention, what I 60 claim and desire to secure by Letters Patent, is:

A hinge comprising hollow members having alined knuckles and also having notches in their edge portions adjacent to the 65 knuckles, a pintle connecting the knuckles, said members further having a shank and also having longitudinal fins on the shank, said fins being of a corresponding thickness from their bases to their free longitudinal edges and throughout their areas, and closure plates adapted to be arranged 70 over the open sides of the hollow members and fastened to the elements to which the hollow members are affixed and having 75 flanges seated in the said notches of the hollow members.

In testimony whereof I have hereunto set my hand in presence of two subscribing witnesses.

RICHARD W. HUBBARD.

Witnesses:

WAUNITA S. SMITH,
WILLIAM GAPE.
